UNITED STATES PATENT OFFICE.

ALFRED KURTZ, OF BROOKLYN, NEW YORK.

LINING FOR HATS.

1,216,140.

Specification of Letters Patent. Patented Feb. 13, 1917.

Application filed June 29, 1916. Serial No. 106,594.

To all whom it may concern:

Be it known that I, ALFRED KURTZ, a citizen of the United States, and a resident of the city of New York, borough of Brooklyn, in the county of Kings and State of New York, have invented a new and Improved Lining for Hats, of which the following is a full, clear, and exact description.

- 10 Among the principal objects which the present invention has in view are: to provide a lining of the character mentioned having incorporated between the side piece and crown piece thereof, an exposed cord; 15 to provide means for holding said cord in service relation; and to provide means for concealing the raw edges of said cord.

Drawings.

20 Figure 1 is a perspective view of a lining constructed and arranged in accordance with the present invention, the side piece of the lining being turned back to show the crown piece thereof;

25 Fig. 2 is a section, the section being taken as on the line 2—2 in Fig. 1;

Fig. 3 is a detail view on an enlarged scale, showing fragments of the crown piece, side piece, and exposed cord therefor;

30 Fig. 4 is a detail view illustrating the method of laying the cord between the crown piece and side piece;

Fig. 5 is a detail view on an enlarged scale, showing fragments of the crown piece and side piece, and a modified form of holding the cord in service relation thereto;

Fig. 6 is a detail view on an enlarged scale and in perspective, showing a method of mounting the cord preparatory to mounting the same in the lining.

Description.

The trade to which the present invention relates requires that a hat be provided with a lining having a central or crown piece 11, a side piece 12, and a cord-like member 13 sewed in the seam between the crown piece and side piece. Heretofore this has been supplied by covering a cord, the covering material having a narrow edge which

is sewed or otherwise joined close to the cord and at the side thereof. This has proved objectionable in that the cord by reason of the covering has been deprived of its characteristic appearance.

In the present invention, an uncovered cord 13 is employed, which is secured between the crown piece 11 and the side piece 12 by the stitching forming the same passing therethrough.

When employing a sewing machine for making the improved lining, a special attachment is provided for feeding the crown member, side member, and the cord member 13.

In Fig. 6 of the drawings, a modified form of the invention is shown, the modification consisting in providing the cord 13 with a strip of material folded upon itself to form edges 14 which may be placed between the edges of the crown piece and the side piece, as shown best in Fig. 5 of the drawings, to more securely hold the cord in its service position.

As viewed when in service, the lining 75 presents a neat and finished appearance wherein the flat crown piece and full side piece are apparently joined by the cord 13, the same resting in the seam between the said crown and side pieces.

Claims.

1. A hat lining comprising a crown piece; a side piece; an uncovered cord exposed between said crown piece and side piece; and means for securing said crown piece, side piece and cord together for forming an ornate seam between said crown piece and side piece.

2. A hat lining comprising a crown piece; a side piece; an uncovered cord exposed between said crown piece and side piece; and means for securing said crown piece, side piece and cord together for forming an ornate seam between said crown piece and side piece; said means embodying a single row of stitching passing through said crown piece, side piece and cord.

ALFRED KURTZ.
